ABSTRACT OF THE DISCLOSURE

In the method, an elongated tube is compacted, gas sterilized, filled with a sterilized solution to elongate the same and then selectively partitioned into discrete units.

BACKGROUND AND SUMMARY OF THE INVENTION

This invention is an improvement on the prior U.S. Pat. No. 3,376,687 of Theodore H. Gewecke. In that patent, a method was disclosed which was useful in the preparation of sterile solutions, particularly those employed for parenteral purposes. The art in this area, as well as in sterilized solutions in general, makes use of involved apparatus and procedures which are primarily an outgrowth of the older methods employing glass bottles. The invention here is a departure from the established art and in one embodiment makes use of a novel filter and manifold arrangement to substantially lessen the complexity of equipment and procedure for the preparation of sterile solutions.

DETAILED DESCRIPTION

The invention is described in conjunction with an illustrative embodiment in the accompanying drawing, in which—

FIG. 1 is a fragmentary perspective view of a tube employed in the practice of the invention, i.e., the bag providing means at an intermediate stage of manufacture;

FIG. 2 is a perspective view of the apparatus used for sterile fill in an early stage of usage;

FIG. 3 is a fragmentary perspective view of the apparatus of FIG. 2 but at a subsequent stage of operation; and

FIG. 4 is a perspective view of an individual unit sterile filled according to the teachings of the invention.

In the illustration given and with particular reference to FIG. 1, the numeral 10 designates generally an elongated tube which is advantageously constructed of flexible, transparent plastic material. Depending upon the usage, many materials may be employed. For example, polyvinyl chloride, polyethylene, vinyl vinylidene chloride, nylon, etc. may be used. The tube 10 is seen to be relatively elongated and equipped at longitudinally spaced points with outlets as at 11 and hanger holes as at 12. One end is closed by a transverse seal or union as at 13 and the other end is equipped with an inlet fitting as at 14.

Following the preparation of the tubing 10, the element is compacted, i.e., rolled upon itself as shown in FIG. 2 and generally designated 15. Alternatively and equally as advantageous in some instances, other compacting arrangements may be employed such as reverse folding, arranging the same in a serpentine configuration,

2

etc. In FIG. 2, two such units are illustrated but it will be appreciated that a lesser or greater number may be utilized. Coupling the units 15 to a microbiological filter 16 is a manifold 17. The filter 16 advantageously may be of the construction provided by Millipore Corporation of Bedford, Mass. The filter 16 is equipped with a liquid inlet 18 and the manifold 17 is equipped with valved couplings as at 19, and 20. The valve couplings 18—20 permit the rapid separation of discrete units or portions 10 of the assembly seen in FIG. 2.

In the practice of the invention, the assembly seen in FIG. 2 is subjected to gas sterilization in an enclosure 21 depicted schematically. Any conventional gas sterilization unit may be employed using, for example, sterilizing 15 gas such as ethylene oxide disclosed in the earlier issued patent.

Following sterilization of the assembly seen in FIG. 2, the assembly is placed partly on a platform 22 (see FIG. 3), with the units 15 placed on a sloping conveyor

20 23. The inlet 18 of the filter 16 is coupled to a source of solution (illustrated schematically as at 24) and solution is caused to flow into the units 15, causing them to unroll to the configurations designated 25 in FIG. 3. After the units 25 have been filled, the discrete bags 26 25 are developed by simultaneously separating out discrete portions of the fluid and transversely heat sealing or otherwise uniting opposing walls of the tubing making up the units 25.

We claim:

30 1. In a method of preparing a package solution comprising sequentially installing outlet fittings at longitudinally spaced points along elongated webbing, forming said webbing into an elongated tube with one end closed, coupling the other end of said tube to a microbiological 35 filter, gas sterilizing the assembled filter and tube, coupling said filter to a source of solution and filling the tube, and cross sealing intermittently the elongated tube to provide discrete units having a predetermined volume of fluid therein.

40 2. The method of claim 1 in which a plurality of tubes is provided with a manifold interposed between said filter and each of said tubes.

3. The method of claim 1 in which said tube is initially compacted.

45 4. The method of claim 3 in which said tubes are initially rolled to provide the compacting thereof and thereafter unrolled incident to filling.

50 5. In a method of preparing a packaged solution comprising sequentially introducing outlet fittings at longitudinally spaced points along an elongated webbing, forming said webbing into an elongated tube with one end closed, compacting said webbing, gas sterilizing the assembled tube, coupling the other end of said tube to a source of sterilized fluid, filling said tube, and cross sealing the tube intermittently to provide required 55 volumes.
